MASSAGE DEVICE

John F. Klaes, Denver, Colo., assignor, by mesne assignments, of one-half to J. Scott Hyde, Denver, Colo., and one-half to Helen Margaret Klaes, San Francisco, Calif.

Application November 17, 1938, Serial No. 240,964

1 Claim. (Cl. 128—57)

This invention relates to massage devices of roller type adapted for use in the treatment of human ills and pains, and has as an object to provide an improved construction for and arrangement of elements in such a device.

A further object of the invention is to provide an improved roller-type massage device which is susceptible of convenient modification for variation in the character and degree of its effect.

A further object of the invention is to provide an improved roller-type massage device adapted for thorough and convenient sterilization.

A further object of the invention is to provide an improved arrangement of pressure-transmitting elements in a roller-type massage device, whereby all portions of an area traversed by such device are manipulated and massaged without undesirable concentration of pressure on certain points or sections of the area.

A further object of the invention is to provide an improved construction and arrangement of handle means adapted for the convenient and effective manipulation of a roller-type massage device.

A further object of the invention is to provide an improved roller-type massage device that is simple of manufacture, positive and efficient in operation, adaptable to a wide variety of specific uses, and which requires no maintenance.

My invention consists in the construction, arrangement, and combination of elements as hereinafter set forth, pointed out in my claim, and illustrated by the accompanying drawings, in which—

Figure 1 is a diagrammatic development of the cylindrical working surface of the improved device. Figure 2 is an end elevation of a simplified embodiment of the invention. Figure 3 is a section longitudinally of the showing of Figure 2. Figure 4 is a plan view of the showing of Figure 2 wherein is illustrated an alternative form or modification of the handle means. Figure 5 is a fragmentary section, on an enlarged scale, longitudinally of a modified construction of the improvement. Figure 6 is a fragmentary, detail section similar to Figure 5 and illustrating further modification of the structural embodiment of the invention. Figure 7 is a section similar to Figure 6 illustrating a still further modification of the structure comprising the invention. Figure 8 is a section longitudinally through a structural embodiment of the invention. Figure 9 is a transverse section of and at right angles to the showing of Figure 8. Figure 10 is a fragmentary,

detail elevation, partly in section, of a structural arrangement advantageously employed in the embodiment according to Figures 8 and 9. Figure 11 is a fragmentary, longitudinal section illustrating a modified construction of the device. Figure 12 is a fragmentary detail section transversely of the showing of Figure 11.

The improved device consists, essentially, of a cylindrical roller mounted for rotation about its axis in and carried by handle means whereby the roller may be manipulated in engagement against an area of the human body, and provided with pressure-transmitting elements or fingers fixed in spaced relation on and projecting radially from the cylindrical surface of said roller. As shown in Figures 2, 3, and 4, a simple embodiment of the invention comprises a hollow, cylindrical roller 15, formed of any suitable material, preferably magnetically-susceptible metal, in any desired manner. The ends of the roller 15 are traversed by parallel plates or spiders 16 disposed in perpendicular relation with the cylinder axis and provided with bores aligned on the cylinder axis to receive and rotatably engage with pins 17 engaged with and extending inwardly from a handle assembly. The handle assembly preferably consists of a pair of identical, V-shaped end frames 18 and grip bars 19 interconnecting in fixed or integral relation between corresponding free ends of the frames 18. The pins 17 are engaged with and extend inwardly from the apices of the frame 18 and, when engaged in the journal bores of the roller 15, mount the handle assembly with its end frames 18 parallel with the end portions of the roller and the grips 19 parallel with the axis of the roller, so that an operator may conveniently grasp the grips 19 and roll the device back and forth across an area to be treated while applying such downward pressure as may be deemed desirable. Washers 20, or like spacing elements, are engaged about the pins 17 between the end frames 18 and the adjacent end portions 16 of the roller to insure free rotation of the latter relative to the handle assembly. In Figure 4 is illustrated a modified handle assembly wherein one of the grips 19 is replaced by a structurally equivalent bar 19' connecting between corresponding free ends of the frames 18 and supporting a handle grip 21 suitably engaged with its midportion and extending outwardly and radially of the cylinder 15 from said bar, which handle arrangement facilitates pushing and pulling of the roller across a surface engaged there-

by while a considerable downward pressure is applied to and transmitted through the grip 19 of the modified arrangement.

The surface of the roller 15 supports a plurality of pressure-transmitting fingers 22 formed integrally on or suitably fixed to said cylinder to project radially therefrom in suitably patterned, spaced relation. The fingers 22 are formed with smoothly convexed ends adapted to engage against and manipulate the area under treatment, and are of a size to agitate and manipulate human flesh without pain or discomfort. In Figure 3, the fingers 22 are shown as formed integrally with the cylinder 15, but it is to be understood that said fingers might well be separately formed and removably or fixedly engaged with said cylinder in any conventional and well-known manner. The diagram of Figure 1 illustrates the pattern for a preferred arrangement of the fingers 22 on the cylinder 15, though such pattern is susceptible of infinite variation without departing from the principle of the invention. As shown in the diagram, the fingers 22 are so placed as to be in staggered relation circumferentially, longitudinally, and diagonally of the cylinder 15, thus insuring that a finger 22 is brought into manipulating engagement with every portion of the area traversed by the roller during actuation of the latter, so that adjacent fingers 22 massage or manipulate immediately adjacent but not identical areas, and that no one area is subjected to repetitious pressure by successive fingers to such an extent as would cause pain or discomfort. When the end walls 16 of the cylinder are formed as closure plates, holes 23 are provided through said walls to permit access of sterilizing agents to the interior of the roller assembly.

The construction hereabove described is susceptible of advantageous employment as a mechanical device, but in the treatment of certain conditions its beneficial effect may be enhanced by charging the roller assembly, and more particularly the fingers 22, with magnetism. When the fingers 22 are formed separately from and subsequently fixed to the roller 15, it is obvious that said fingers may be of magnetically-susceptible material while the roller itself is of magnetically-non-susceptible material, in which event the fingers alone would be magnetized and productive of a consequent therapeutical effect equal if not superior to that resulting when the entire roller assembly is magnetized.

In the modified construction shown in Figure 5, the essential elements of the invention are in all respects identical with that previously described, the modifications being structural and mechanical only, and consisting of the addition of anti-friction bearings 24 operatively between the pins 17 and end walls 16 of the roller assembly, and the provision of a removable and replaceable sleeve 25 carrying the fingers 22 and adapted to telescope over and be suitably secured, as by means of screws 26, to the smooth cylindrical surface of the cylinder 15, thus providing means for conveniently changing the size, character, and specific pattern or arrangement of the fingers 22 by substitution of one sleeve assembly for another in operative relation with a single roller and handle assembly.

Figure 6 illustrates the use of removable rubber, or like yieldable, covers or envelopes 27 on the manipulating ends of the fingers 22 for cushioning modification of the normal action of such fingers. In Figure 7 is shown an arrange-

ment of removable sleeve 25' and fingers 22' formed of relatively yieldable or resilient material, such as rubber, which construction is of particular advantage for initial treatments on sensitive flesh or where a manipulation of a degree more moderate than can be obtained through the use of rigid fingers is desired.

In Figures 8, 9, and 10 is illustrated an embodiment of the invention particularly adapted to carry and transmit the force of magnetism. In this latter embodiment, the roller assembly is formed of two identical, semi-cylindrical portions 15', each being provided with complementary end wall portions 16' and carrying its complement of fingers 22, which portions are adapted to be joined on an axial plane to form a complete cylindrical roller assembly. The portions 15' are formed of magnetically-susceptible material and, when joined, are magnetically isolated from each other. In the arrangement shown, spacer elements 28, of magnetically-non-susceptible material are interposed between meeting edges of the portions 15' said elements being shown as provided with oppositely-extending studs adapted to engage in holes in the margins of the portion 15' to suitably position and hold said elements against displacement, and connecting elements 29, of magnetically-non-susceptible material in the form of bolts or screws, engage between the portions 15' and diametrically of the roller assembly to firmly clamp and hold said portions together and in the slightly spaced relationship resulting from the use of the spacer elements 28.

Figures 11 and 12 illustrate a mechanical modification of the constructions hereabove described which is of notable advantage in maintaining a permanent magnetism in the pressure-transmitting studs or finger elements of the roller assembly. While this latter construction is susceptible of incorporation with a unitary roller of the type indicated at 15 in Figures 3, 4, and 5, it is more practically combined with the split roller construction illustrated in Figures 8 and 9, since the separable roller halves 15' permit of more convenient access to the interior thereof. The latter modification consists in the employment of U-shaped units of magnetically-susceptible material to form the pressure-transmitting elements of the roller assembly, such units constituting, when magnetized, permanent magnets of horseshoe type whereof one terminus is of one magnetic characteristic and the other terminus of the opposite characteristic, as is the nature of horseshoe magnets. In Figures 11 and 12 the pressure-transmitting fingers are indicated by the numeral 22'' and are shown as being suitably paired by means of an integral, curved portion 30 interconnecting between adjacent finger elements. The U-shaped units thus formed are seated through holes in the roller shell 15' so that the curved portions 30 are within the shell and the finger elements 22'' project radially and outwardly through the shell to the degree and in the manner hereabove set forth, the shell construction utilized for this modification being preferably of magnetically-non-susceptible material. The U-shaped units may be fixed in or secured to the roller shell 15' and in the desired relationship with said shell in any suitable or desired manner, but a practical and convenient method of so securing the units relative to the shell is to fill that portion of the shell interior occupied by the curved arches of the units with a plastic material which

will harden in position and thus retain the finger units against relative displacement, certain cements, and the like, being readily available and entirely adequate to such purpose, the use of such a stabilizing filler being indicated by the 5 numeral 31. The filler 31 is also of advantage in increasing the weight of the assembly, thus minimizing the necessity for downward pressure applied by the operator to obtain the desired degree of massage.

Since the improvement is susceptible of material modification and variation in the specific form, construction, arrangement, and association of its various elements, all without departing from the spirit and principle of the invention, 10 15 I wish to be understood as being limited solely by

the scope of the appended claim, rather than by any details of the illustrative showing and foregoing description.

I claim as my invention:

5 Massage apparatus comprising a handle frame and a roller assembly journaled for rotation about its axis in said frame, said roller assembly comprising a hollow, cylindrical shell and a plurality of identical, U-shaped elements, 10 each formed to provide a pair of parallel, cylindrical fingers having smoothly rounded tips, disposed with their parallel members intersecting said shell to project radially, uniformly, and in closely-spaced relation outwardly therefrom.

JOHN F. KLAES.
